UNITED STATES PATENT OFFICE.

DORA RAY, OF TARENTUM, PENNSYLVANIA.

FRUIT-JAR.

SPECIFICATION forming part of Letters Patent No. 711,260, dated October 14, 1902.

Application filed January 30, 1902. Serial No. 91,882. (No model.)

To all whom it may concern:

Be it known that I, DORA RAY, a citizen of the United States of America, residing at Tarentum, in the county of Allegheny and State of Pennsylvania, have invented certain new and useful Improvements in Fruit-Jars, of which the following is a specification, reference being had therein to the accompanying drawings.

10 This invention relates to certain new and useful improvements in fruit-jars, and has for its object a device of this character which will effectually exclude all air from gaining ingress to the contents, thereby spoiling the same.

15 My invention has for its further object a fruit-jar in which the top or cover proper shall be held into engagement with the upper portion of the neck of the jar in a manner 20 that will effect a sealing contact between the neck and the top.

25 My invention further resides in the novel details of construction and combination of parts to be hereinafter more clearly described, and fully set forth in the claim.

30 In describing the invention in detail reference is had to the accompanying drawings, forming a part of this specification, and wherein like numerals of reference indicate like parts throughout the several views, in which—

35 Figure 1 is a vertical sectional view taken on the line xx of Fig. 2, showing my invention applied to the fruit-jar. Fig. 2 is a side elevation thereof.

40 The fruit-jar (designated by the reference-numeral 1) carries the usual neck portion 2, at the upper extremity thereof being formed an integral annular bead 3, adapted for engagement with and to limit the upward movement of the binding-wire 4, which has its ends twisted, as at 5, in order to effect a secure engagement with the periphery of the neck of the jar. As shown at 6 6, this wire has a series of coils or convolutions formed 45 thereon at points diametrically opposite one another, receiving the downwardly-extending ends 7 of the fastening means. The fastening means comprise an integral wire which is bent upwardly from the ends 7 in a substantially transverse direction thereto, the wire then having the coil formed thereon, as

at 8, forming the eye. The wire is then bent into a substantially semicircular form, as indicated at 9, which semicircular portion lies in a plane transversely to that assumed by 55 the upwardly-extending ends of the fastening means.

Secured in the eye 8 are inwardly-extending ends 11, formed integral with the fastener proper, 12. This fastener at its upper end is 60 bowed downwardly, as shown at 13, and engages in the seat or notch 14, formed in the upper end of the integral rubber boss 15, which is interposed between the depending portion of the fastener proper and the upper face of 65 the jar closure or top 16. Formed integral with the interior of the neck of the jar are two suitably-spaced annular interior flanges 17 18, the upper one, 17, receiving the rubber gasket or washer 19, adapted for engagement with 70 the under face of the jar closure or top 16, thereby effecting a sealing contact therewith. The second flange, 18, receives upon its upper face an annular disk 20, which may be suitably waxed or otherwise oiled in order to render the same impervious to the action of the fruit or other preserved substance. It will be noted that this disk is of sufficient rigidity 75 to retain its relative position in relation to the interior of the jar-neck, with which it 80 forms a sealing contact.

It will be noted that the under face of the jar-closure 16 is cut away, as shown at 21, forming a shoulder 22, which engages with the upper interior edge of the neck of the jar. 85 After the fruit or other substance to be preserved has been placed in the jar the waxed or oiled disk 20 is placed upon the flange 18 and is in engagement with the upper face thereof, as well as the interior of the neck of 90 the jar. The gasket or rubber washer 19 is then placed similarly upon the upper face of the flange 17, and the jar top or closure 16 is then placed in position, the convexed face of which engages with the interior of the upper 95 inner edge of the gasket or washer. The jar is then in condition to receive the rubber boss 15, which is engaged by the depending portion 13 of the fastener proper in its seat, and the semicircular portion 9 is then pressed 100 downwardly, which will cause the boss 15 to become seated upon the upper face of the

jar-closure 16 and retain the same in sealing contact with the upper end of the neck of the jar.

While I have illustrated in the accompanying drawings the boss as being of a substantially square shape, still I do not wish to limit myself to the particular contour of the same, it simply being necessary that the boss should have the lower portion of sufficient size in order for the same to securely seat upon the upper face of the jar-closure. Other such minor changes may be made in the details of construction and combination of parts without departing from the general spirit of my invention.

Having fully described my invention, what I claim as new, and desire to secure by Letters Patent, is—

In a fruit-jar or the like, the combination with the gasket supported on the interior of the jar-neck, of a jar-closure having a convex under face engaging said gasket, and means for securing the jar-closure in sealing contact with said gasket comprising a wire encircling the jar-neck and secured thereto and carrying eyes having a lever secured therein, a bail having a downwardly-bowed portion, and a notched rubber boss engaging the said bowed portion of the fastener proper and seated on the upper face of the jar-closure.

In testimony whereof I affix my signature in the presence of two witnesses.

DORA RAY.
